UNITED STATES PATENT OFFICE.

STANLEY P. THOMPSON, OF SEATTLE, WASHINGTON.

TIME AND DATE INDICATOR.

1,311,101.

Specification of Letters Patent.

Patented July 22, 1919.

Application filed July 29, 1918. Serial No. 247,164.

To all whom it may concern:

Be it known that I, STANLEY P. THOMPSON, a citizen of the United States, and resident of the city of Seattle, county of King, 5 and State of Washington, have invented certain new and useful Improvements in Time and Date Indicators, of which the following is a specification.

My invention relates to devices employed 10 for determining by direct reading, the time elapsing between different dates, the dates upon which certain time periods begin or end, and the day of the week of any date, either in the past or future, and for determining questions relating to time and dates. 15 It may, therefore, be called an adjustable and universal time indicating calendar.

The object of my invention is to provide 20 a device for the use, more particularly, of people handling business connected with financial transactions involving the figuring of interest, discount, and dates when obligations become due, and to provide a device which may furnish the information of this 25 kind which is desired both expeditiously and with as little requirement for mental figuring as is possible, while at the same time contributing to accuracy of result.

The principles of my invention and the 30 manner of its use will be hereinafter described and are illustrated in the accompanying drawings, in the particular form of construction which I now most prefer to use. The features which I consider to be novel 35 and upon which I desire patent protection, will be particularly defined by the claims which terminate this specification.

Figure 1 is a face view of the complete 40 device.

Fig. 2 is a transverse section taken on a radial line on line 2-2 of Fig. 1.

Fig. 3 is an enlarged face view showing 45 a quadrant which contains the indicating table or chart by which the device is set to adjust it for any particular year.

Fig. 4 is an enlarged face view of the quadrant which contains the scale used to 50 adjust the relations of the days of the week at the beginning and ending of the year.

In banks and business houses having to 55 do with discounts and interest payments, it is desirable and saves much time, as well as contributing to accuracy, to have some device which may be quickly operated to indicate the time factors of the problems as they come up. It is the purpose of my in-

vention to provide an easily operated device which will do this and which is also accurate and reliable. The particular construction shown in the accompanying drawings will herein be specifically described as being that now preferred by me, although not necessarily being the only construction which falls within the scope of my invention. 60

The physical construction of the device as 65 illustrated is as follows.

A card or plate 4 forms the base upon which the movable parts are pivoted, as by a pivot 11. These pivoted or rotatable parts comprise the disks 2 and 3 and the disk 1, 70 the disks 2 and 3 being parts which directly contribute to the functioning of the device, while the disk 1 is more of a convenience than an essential.

The disk 1 functions chiefly as a weight 75 or washer to hold the disks 2 and 3 in shape and prevent their being bent up or broken and to hold them closely against each other and down upon the base 4. This disk 1 may be made of metal, wood, or of any suitable 80 artificial fiber or plate material. It is preferably turnable on the pivot 11, although it might be fixedly secured to the base 4.

The disk 2 has two circular bands or 85 columns of figures, 20 and 21, just within its periphery and without the periphery of the disk 1. These bands contain 365 spaces which are serially numbered, the figures of one column increasing in one direction while the other increases in the opposite direction. 90 The reading is taken from one of these columns for dates in the future and from the other column for dates in the past.

The disk 3 has two bands or rings, 95 30 and 31, just within its periphery. The band or ring 31 is divided into twelve sectors, one for each month of the year, each being provided with the name of the month which it represents and extending over as many of the day spaces as there are days in the 100 month. The day spaces in these sectors are numbered from one up.

The base 4 has a circular ring just without the periphery of the disk 3 which is laid out in 365 equal spaces, similarly to and 105 matching with the numbered spaces in the rings 20 and 21 of disk 2, and the numbered spaces of ring 30. In these spaces the names of the days of the week are printed in their proper sequential order. As the ring 30 has 110 therein the date numbers of the months and it is adjustable relative to the ring 40, if the

disk 3 be properly set, the day of the week upon which any date has fallen or will fall, may be immediately observed.

At one or more places on the base 4, for convenience preferably in the corners of the square outline thereof, are placed a list or lists, 6, of year numbers, arranged in serial relation, with all leap years given twice, one of these duplicate year numbers preferably being contrasted, by color or otherwise from the other, to facilitate operation and instruction. I have shown the first of each of these duplicate year numbers by white figures on a black ground. In printing, the ground may be any suitable color and the figures may be then printed in black, as are the others, the color contrast of the background being sufficient to secure the attention desired.

The extent of these year numbers may be made anything desired. The spaces occupied conform with the spacing of the rings 20, 21, 30 and 40, and the year numbers are so placed with relation to the numbering on these rings, that when the pointer 32, carried by the disk 3, is placed opposite any year number, it will bring the numbers in the month segments of ring 30, in relation with the days of the week, as shown in the ring 40, corresponding with that actually existing in that year. The disk 3, together with the base 4, thus becomes a calendar good for whatever period is represented by the numbers in the segments 6. These may be extended as far as desired.

Excepting in leap years, the first and last days of each year come on the same day of the week. In consequence, Dec. 31 and Jan. 1, as shown on the days-of-the-week circle 40, must show the same day of the week for these two adjacent spaces in circle 40. To secure this when the device is adjusted for a series of years, I provide the following means.

Secured to the disk 3 is a segment 5 of a transparent material, as of clear celluloid, which extends a distance each side of the line representing the termination and the beginning of the year. On the base 4 is provided a sector 41, just outside the ring 40, having days of the week printed therein, this covering an arc which covers the maximum adjustment given the disk 3 in setting it for the different years, and includes therein the beginning and end of the year as indicated thereon. This extends over an arc equal to that of the transparent plate 5. The days of the week as shown on this sector are arranged sequentially, and consequently, they are one behind those for the month of January, in the part which is opposite that month.

The plate 5 has two segments, 50 and 51, which are made opaque, or at least sufficiently opaque to screen or obscure what-

ever is behind them. As this screen or shutter plate is mounted upon the disk 3 which carries the monthly indications, it moves with it. It, therefore, screens the names of the days in the ring 40 by the opaque segment 51 and the names of the days in the sector 41 by the opaque segment 50. In consequence, as the disk 3 is adjusted for the year, as indicated upon the segmentally arranged table 6, two like days of the week are at all times maintained together at the ends of the year except leap year. The angular extent of the plate 5 should equal twice that of the maximum length of the segment occupied by the years table 6.

In using my device the pointer 32 is set to indicate the year. If this is a leap year, the pointer is set upon the black space containing the year, for all dates in January and February, and on the white space containing the year number for the remainder of the year.

If it is desired to determine a date any number of days ahead or back from a given date, the disk 2 is turned so as to bring the arrow 12 and the space containing the figures 365, opposite the date as shown in ring 30, from which the computation is to be made. If the date is one in the future, the inner ring 20 is used, this being followed around until the figure representing the desired number of days is reached, opposite which in column 30 will be found the date. If the date is one in the past, the ring 21 is used in like manner.

If the number of days intervening between two dates is desired, the disk 2 is similarly set on one of the dates and the number found opposite the other date gives the number of days which intervene.

By using the ring 40, or 41, showing the days of the week, the condition as to Sundays and holidays of the date of beginning and ending of any time period, is shown, and the date of actual payment of an obligation with the true interest or discount period, may be exactly and immediately told.

It is believed that the manner of operating the device has been sufficiently described so that further amplification thereof is not necessary. In using a cover plate or disk, as 1, I prefer that it be secured in some way to turn with the uppermost indicating disk, that is, with the disk 2.

The pointer 32 may be made of a size to give a sufficient upward projection that it may form a convenient handle by which to turn the disk 3.

In using this device it would be set for the day and left in this adjusted form, until it was necessary to figure a problem based upon another date.

What I claim as my invention is:

1. A date indicator comprising two disks

- mounted for relative rotative movement about a common point, one of said disks having thereon a circular band with the months of the years and the numbers of the days in 5 the months, arranged in sequential order, the other having an adjacent ring containing the days of the week arranged in sequential order, and alongside of this an arc having therein the days of the week arranged 10 in sequential order and extending each way from the point in said ring which represents the first of the year, said markings in the arc matching with the markings of that part of the ring which represents 15 the month of December, and a screen carried by the other disk and having two opaque segments extending from a common central point in opposite directions, one acting to screen the days of the week in the ring and 20 the other to screen the days of the week in the arc.
2. A date indicator comprising two disks mounted for relative rotative movement about a common center, one of said disks 25 having the months and the days of the month upon a peripheral band and the other having adjacent to said band and arranged in

sequential order the days of the week for the year spaced to match with the figures of the first named band, and also having 30 alongside its own ring and extending in opposite directions from the point representing the first of the year, a set of names of the days of the week similarly spaced and arranged to match with those of the ring 35 which lie just prior to the end of the year, a screen carried by the first named disk and having two opaque segments extending oppositely from a common point and adapted respectively to cover a part of the main ring 40 representing the days prior to January first and the other to cover a part of the supplemental arc representing the days after December 31st, one of said disks having a segmental table giving the years and the other 45 having a pointer coöperating with the said table.

3. A device as in claim 2 in which leap years are given a double spacing in said table.

Signed at Seattle, Washington, this 22nd day of July, 1918.

STANLEY P. THOMPSON.
